UNITED STATES PATENT OFFICE.

FRANK W. PERRY, OF PHILADELPHIA, PENNSYLVANIA, ASSIGNOR TO THE HERO FRUIT JAR COMPANY, OF SAME PLACE.

DESIGN FOR A CALENDAR-MOUNT.

SPECIFICATION forming part of Design No. 20,677, dated April 14, 1891.

Application filed February 16, 1891. Serial No. 381,709. Term of patent 3½ years.

To all whom it may concern:

Be it known that I, FRANK W. PERRY, a citizen of the United States, and a resident of Philadelphia, Pennsylvania, have invented a 5 Design for a Calendar-Mount, of which the following is a specification.

My design is fully shown in the accompanying drawing, which represents a perspective view of the calendar-mount.

10 The main support is a reproduction of the well-known statue of "Liberty Enlightening the World," the novel feature of the design being the calendar-leaf-suspending devices upheld by the statue, these parts consisting of 15 the calendar-card *a*, with its leaves, the sup-

porting-bar *b*, projecting horizontally from the uplifted torch of the statue, and the depending hangers *d*, whereby the card *a* is suspended from the bar *b*.

I claim—

20 The design for a calendar-mount, substantially as described, and as shown in the accompanying drawing.

In testimony whereof I have signed my name to this specification in the presence of 25 two subscribing witnesses.

FRANK W. PERRY.
